UNITED STATES PATENT OFFICE.

HENRY CLAY WADE, OF NEW YORK, N. Y.

APPARATUS FOR GENERATING GASEOUS FUEL.

1,261,463.

Specification of Letters Patent.

Patented Apr. 2, 1918.

Application filed December 18, 1916. Serial No. 137,568.

To all whom it may concern:

Be it known that I, HENRY CLAY WADE, a citizen of the United States, residing at New York, in the county of New York and State of New York, have invented certain new and useful Improvements in Apparatus for Generating Gaseous Fuel, of which the following is a specification.

This invention relates to apparatus for generating gaseous fuel and particularly to that type of apparatus disclosed in United States Patent No. 1,121,695 granted December 22, 1914.

The invention will be understood by reference to the accompanying drawings in which,

Figure 1 is a sectional elevation of a combined generator and burner embodying the improvements; Fig. 2 is a sectional plan view of the same on the line 2—2 of Fig. 1; and Fig. 3 is a diagrammatic view of the apparatus.

Referring to the drawings, the combined generator and burner A is constructed as a cup-shaped member having a rim or flange 1, in which is formed a circular generating chamber 2, having an inlet port 3 separated by web 4 from an outlet port 5. The stem *a* of the cup-shaped member rises from a base 6, and is formed internally with an expansion chamber 7 communicating at its top with a burner tip 9 which is tapped into a threaded aperture 8. The generating chamber receives the heat of a flame issuing from the burner tip 9, and means are provided for deflecting the flame so that it may be directed against the inner wall of flange 1. To that end the burner head is covered by cap plate 11, formed with a central aperture 12 through which the flame from the burner tip is projected into contact with a deflecting plate 13. The deflecting plate is provided with a series of annularly arranged perforations 14 through which the flame passes into direct contact with the inner wall of the generating chamber 2, the said wall serving to deflect the flame upwardly. The burner head *a* is formed with a series of openings 10 through which air may pass to the burner tip for the purpose of aiding combustion.

The inlet port 3 of the generating chamber 2 communicates with a pipe 15, which in turn communicates with the branch pipe 16 connected with the pipe 17 leading to an

oil tank B and connected also with the pipe 18 leading to a water tank C. Communication between the branch pipe and the oil pipe 17 is controlled by a valve *o*, and communication between the branch pipe and the water pipe 18 is controlled by a valve *w*. Each of the tanks may be provided with a level gage 19 and one of the tanks may be provided with a pressure gage 20. In the present embodiment of the improvements communication between the tanks is effected by means of an air pipe 20', so that air under pressure admitted to the water tank will have equal effect in the oil tank. It will be understood that means may be provided for varying the pressure in one tank relative to the pressure in the other tank, if desirable. In the arrangement shown in Fig. 3 of the drawing, a conventional hand pump D is shown for creating air pressure in the tanks. The pump is connected by means of pipe *d'* with the tank C near the upper end of the latter, a valve *d''* being provided for controlling communication between the pump and the tanks.

By the aforesaid tank arrangement, an emulsion of oil and water may be conveyed under pressure to the generating chamber 2 via the inlet port 3. It is desirable that the emulsion be sprayed into the generating chamber, and to that end the piping aperture may be reduced in diameter at the inlet port, or any suitable means for creating this spray may be provided.

The emulsion leaves the generating chamber in the form of gas, and the gas is conveyed to expansion chamber 7 and thence to the burner 9. To that end the outlet port 5 of the generating chamber communicates with the pipe 21, the latter being tapped into the stem *a* of the burner and communicating with the expansion chamber 7. For the purpose hereinafter described the generating chamber near outlet port 5 is provided with a coil X of metal possessing catalytic power, and a mesh of like metal is disposed within the expansion chamber 7. The expansion chamber also communicates with the pipe 22 which may lead to a tank for the storage of surplus gas. In the drawings pipe 22 communicates with a conventional gas burner tip *g*. In the operation of the apparatus the air pressure in the tanks will force the oil and water to the lower vertical portion of pipe 15 where they meet and form an emul-

sion which passes to the restricted outlet point of the pipe at which point the emulsion is sprayed into the generating chamber. The apparatus may be started by burning a liquid fuel, such as alcohol, in the cup portion of the member A surrounding burner tip 9, and the starting fuel may be poured into the cup through one of the ports 10. The flame from the starting fuel passes upwardly into contact with the inner wall of the generating chamber and heats the same sufficiently to vaporize a charge of the hydrocarbon emulsion, the water of the emulsion being converted into steam. As the gaseous vapor approaches the outlet port of the generating chamber it is brought into contact with a metal of high catalytic power and in finely divided form such as a mesh or coil X. This catalyst initiates chemical reactions in the vapor.

It will be understood that the breaking up or cracking of the hydrocarbon is progressive throughout the generating chamber, and that the hydrocarbon is in such a divided state as it approaches the outlet end of the chamber that it would ordinarily deposit free carbon. This carbon, however, comes into contact with the highly heated steam in the presence of the catalyst, and the latter initiates a double reaction, first, by causing the oxygen to break its chemical bond with the hydrogen and to combine with the carbon, forming carbon monoxide, and secondly, by combining the free hydrogen with hydrogen and carbon atoms arising from the breaking up of the hydrocarbon liquid, the whole being subsequently expanded and forming a fixed gas of high calorific power. After passing from the outlet port of the generating chamber the gases pass through pipe 21 to the expansion chamber 7 where they are expanded in the presence of a second catalyst which completes the chemical association of the gases into a fixed gas.

The catalyst should be in a form presenting the largest surface in proportion to its mass, consistent with the requirement that it be disposed so as to maintain its position and not unduly impede the flow

of the gases. Either metallic platinum or nickel possesses the desired action.

It will be understood that various modifications may be made on the form and arrangement of the elements of the apparatus, and therefore the invention is not limited to the precise embodiment herein shown and described.

What I claim and desire to secure by Letters Patent of the United States, is:—

1. In an apparatus of the character described, a generator comprising a base and an upper cup-like section within which a peripheral generating chamber is formed, means for delivering an emulsion of oil and water to said chamber wherein it is vaporized, a burner supported upon said base, and arranged to deliver its flame against a wall of the generating chamber, and means for delivering the gaseous vapor from the generating chamber to the burner. 65

2. In an apparatus of the character described, a generator comprising a generating chamber, a catalyst of metal communicating with said chamber, means for delivering an emulsion of oil and water to said chamber wherein it is vaporized and decomposition of the water vapor is initiated, a burner, and means for delivering the gaseous vapor to the burner. 75

3. In an apparatus of the character described, a generator comprising a generating chamber having inlet and outlet ports, a catalyst located within the generating chamber at the outlet port thereof, means for delivering an emulsion of oil and water to said chamber wherein it is vaporized and decomposition of the water vapor is initiated, a burner, means for delivering the gaseous vapor to the burner, and means for deflecting the flame of the burner against a wall of the generating chamber. 85

In testimony whereof I have hereunto signed my name in the presence of two subscribing witnesses.

HENRY CLAY WADE.
